STRUCTURE FOR MOUNTING SOCKETS AND OTHER DEVICES IN LIGHTING FIXTURES

Julio A. Pascucci, Meriden, Conn., assignor to The Miller Company, Meriden, Conn., a corporation of Connecticut

Application January 14, 1957, Serial No. 634,104

7 Claims. (Cl. 240—51.11)

This invention relates to electric lighting fixtures and more specifically to a new and improved structure for mounting sockets and other devices in electric fixtures.

One object of the invention resides in the provision of a novel and improved support for sockets and other elements in electric fixtures that is characterized by its simplicity, ease of installation and relatively low cost. By reason of a novel and improved arrangement of elements the socket supporting structure can be held in position on the fixture without the need for auxiliary fastening means. In the case of fluorescent fixtures utilizing elongated channel-like housing the socket supporting structure can be arranged to engage opposing walls of the channel and function both as a socket supporting member as well as a stiffening member for the channel. If desired the socket supporting member can further be arranged to provide support for the entire fixture.

Another object of the invention resides in the provision of a novel and improved socket support for fluorescent fixtures wherein the support is arranged to slidably engage and automatically lock in position on the fixture.

Still another object of the invention resides in a novel and improved fixture and socket supporting means therefor.

The above and other objects of the invention will become more apparent from the following description and accompanying drawings forming part of this application.

In the drawings:

Fig. 1 is an exploded view in perspective of a socket supporting structure in accordance with one embodiment of the invention;

Fig. 2 is a fragmentary side view of the embodiment of Fig. 1 showing the first step in securing the socket mounting member to the associated channel member forming part of the completed fixture;

Fig. 3 is a cross sectional view of Fig. 2 taken along the line 3—3 thereof;

Fig. 4 is a fragmentary side view of the invention similar to Fig. 2 but with the socket supporting structure in the locked position; and

Figs. 5 and 6 are cross sectional views of Fig. 4 taken along the lines 5—5 and 6—6 thereof.

The embodiment of the invention illustrated in the drawings is for the purpose of supporting lamp sockets for fluorescent tubes within a suitable channel member that forms a top protective member for the fluorescent tubes and may embody a suitable wire way, reflector or other elements for operation and support of the fixture. In the normal case the outer channel member is generally of U-shaped configuration having downwardly extending side walls. With the socket support in accordance with the invention specially arranged perforations are utilized in the walls of the channel member and the bracket member is provided with appropriate tabs or offset portions arranged to slidably engage the openings in the side walls to lock the socket supporting

2

means in position thereon. In addition when the socket supporting member is in position in a channel it is locked against movement in all directions and two such bracket supporting members on opposite ends of the channel may provide the sole support for the entire fixture. If desired, bracket members may be used as means for securing two or more fixtures in end to end relationship to form a substantially unitary structure with auxiliary means being used to support the structure in an operative position.

Inasmuch as the invention concerns the attachment of a bracket or supporting member in a fluorescent fixture channel, only the top protective channel, of which a portion is customarily employed as the wiring channel, is shown. In the drawings this wiring or protective channel is generally denoted by the numeral 10 and includes a top wall 11 having offset end portions 12 and a pair of side walls 13. For stiffening purposes and for the support of other elements of the fixture the bottom edges of the side walls 13 may be terminated in inwardly formed flanges 14.

The socket supporting member is generally denoted by the numeral 15 and is adapted to span the inside of the channel. It is attached to the side walls 13 by means of engagement of end tabs on the bracket 15 with cooperating openings in the side walls 13. More specifically, each side wall 13 of the channel 10 includes a pair of openings 16 and 17 for each bracket with the corresponding openings in opposing walls being aligned. The opening 16 is generally rectangular in shape while the opening 17 is provided with a rectangular central section 18, a relatively narrow elongated section 19 and a relatively wide portion 20 extending toward the opening 16 and of substantially the same width.

The cooperating tabs on the bracket member 15 for engagement with the openings 16 and 17 include a pair of downwardly extending co-planar tabs 21 and 22 and a central tab 23 that is spaced outwardly from the tabs 21 and 22 so that the spacing between the plane of the outer surface of tabs 21 and 22 and the plane of the inner surface of tab 23 is substantially equivalent to the thickness of the associated side wall 13. In addition to the three tabs described above, the tab 21 is formed with a latching or locking member 24 that preferably constitutes an integral part of the tab 21 and extends outwardly therefrom.

Both ends of the socket supporting bracket 15 are arranged in a similar manner and each bracket is installed by first inserting it between the side walls 13 with the tabs 23 disposed within the central section 18 of their cooperating openings 17. At the same time the locking tab 24 engages the opening 16 since it has a vertical dimension slightly smaller than the vertical dimension of the opening 16. When both sets of tabs 23 and 24 are in engagement with their cooperating openings as shown more clearly in Figs. 2 and 3, the entire bracket assembly 15 is then forcibly moved outwardly of the channel 13 to the position shown in Figs. 4, 5 and 6. Since the locking tabs 24 each have inclined surfaces 24' outward movement of the bracket member 15 will produce a slight deflection of the channel walls 13 without permanently deforming the channel. During this outward movement the upper or neck portion 23' of each tab 23 will engage the elongated slots 19 forming part of the opening 17. When the tabs are seated in the slots 19, the latching tab 24 will snap into the slot 20 forming part of the opening 17 and prevent movement of the bracket 15 inwardly of the channel 10. Since the slots 19 and 20 of the opening 17 snugly engage the tabs 23 and 24 the bracket 15 will be locked against all movement relative to the side walls 13.

From the foregoing description it will be observed that

when the bracket 15 is in place in the channel the tabs 21 and 22 will lie flat against the insides of the walls 13, while the tabs 23 will engage the outer surface of the walls 13. This may be observed more clearly in Fig. 6.

While the fluorescent socket 25, of which only one is illustrated, is preferably secured in place on the bracket 15 prior to mounting of the bracket in the channel 10, it is evident that the socket may be mounted in position after the bracket 15 is in place in the channel. In the drawings the socket 25 is secured to the bracket 15 by a single screw 26 and is locked against movement relative to the bracket 15 by the engagement of a pair of bosses 27 on the socket with cooperating openings 28 in the bracket 15.

In certain cases it may be desirable to connect two or more fluorescent fixtures in end to end relationship to form an elongated unitary lighting fixture. For this purpose the brackets 15 on each end of the channel 10 are preferably mounted so that the outer edge 15' of each bracket 15 is coincident with the outer edge of the channel 10 when in position thereon. To couple the two fixtures one to the other each bracket member 15 may be provided with downwardly extending slotted tabs 29 or other suitable fastening means that will facilitate coupling of the fixtures one to the other. If desired, these tabs may also be used to provide the primary support for the entire fixture.

While only one embodiment of the invention has been shown and described, it is apparent that other modifications, changes and alterations may be made without departing from the true scope and spirit thereof.

What is claimed is:

1. In a lighting fixture having an elongated channel-like member including a pair of substantially parallel side walls, socket mounting means comprising a socket mounting bracket extending between said walls, at least two members on each end of said bracket with the members on each end disposed in spaced planes substantially parallel to said walls, said walls each including openings therein for receiving and slidably engaging the outermost members on each end and means carried by said bracket for engaging said openings to lock the bracket in place between and against movement relative to said walls.

2. In a lighting fixture according to claim 1 wherein the last said means includes an outwardly extending tab carried by each of said innermost members for abutting engagement with a wall of the associated opening.

3. In a lighting fixture according to claim 1 wherein said bracket includes three members on each end with the central member being displaced outwardly from the adjoining members and said openings in the channel walls each include an enlarged central portion and a narrow

elongated portion for engagement of the cooperating outwardly extending member when the bracket is in said locked position.

4. In a lighting fixture according to claim 1 wherein said walls each include a second opening spaced from the first said opening and the last said means comprises an inclined tab on each end of said bracket adapted to be received in its associated second opening upon insertion of the outermost members in the first said openings, said tabs being movable out of the second of said openings and into engagement with the edge of the first said openings upon movement of said bracket into the locked position.

5. A lighting fixture comprising an elongated channel member having a pair of depending side walls, a socket mounting bracket at one end of said channel and means for attaching said bracket to said side walls comprising at least two members on each end of said bracket with the members on each end disposed in spaced planes substantially parallel to said walls, said walls each including openings therein for receiving and slidably engaging the outermost members on each end and means carried by said bracket for engaging said openings to lock the bracket in place between and against movement relative to said walls.

6. A lighting fixture according to claim 5 wherein said bracket includes three members on each end with the central member being displaced outwardly from the adjoining members and said openings in the channel walls each include an enlarged central portion and a narrow elongation portion for engagement of the cooperating outwardly extending member when the bracket is in said locked position.

7. A fluorescent fixture comprising an elongated channel member having depending side walls with each wall having at least one opening spaced from each end thereof, a bracket member spanning each end of said channel, said member having means on the ends thereof for engaging said openings and locking said member in position upon outward movement of the member relative to the channel and fastening means on each bracket member for coupling two or more fixtures in end to end relationship.
